SAVINGS CALENDAR

Hans Jørgen Jepsen, Hellerup by Copenhagen,
and Kai Christian Nielsen, Copenhagen, Denmark

Application July 6, 1933, Serial No. 679,180
In Denmark October 20, 1932

6 Claims. (Cl. 194—94)

The invention relates to a so-called savings calendar, i. e. an apparatus which shows the day of the week, the date and the name of the month or, maybe, only two of these indications, and which is adjusted from day to day by the insertion of one or more coins.

The various calendar indications, such as the name of the day of the week, the date and the name of the month, are arranged along the periphery of discs disposed alongside of one another on a common shaft. The latter is journaled in two side walls interconnected by means of bolts or the like in such a manner that the discs are situated between the said walls. The apparatus is enclosed in a casing fitted with apertures, through which the calendar indications can be read, and a coin-insertion slot by way of which the coins can be inserted into the apparatus.

20 The novel feature of the present invention consists in an especially suitable construction of such a savings calendar, by which the adjustment of the calendar indications is solely effected by the insertion of the coin into the apparatus, without the use of any handle or the like. Thereby the operation of the apparatus is simplified, and any errors due to forgetting to move the handle will be precluded.

One construction of the invention is illustrated 30 on the drawings, in which

Fig. 1 shows the apparatus in front elevation, the front wall of the enclosing casing being removed,

Fig. 2 the apparatus in side elevation, the side 35 wall of the enclosing casing being removed,

Fig. 3 a portion of the view shown in Fig. 2, with the parts in the position they occupy when a coin is being inserted into the mechanism,

Fig. 4 the same view, partly in section, with 40 some of the parts removed,

Fig. 5 a detail in perspective view,

Fig. 6 a detail view of the mechanism serving to adjust the disc, the periphery of which carries the name of the day in the week,

Fig. 7 a similar view of the mechanism adjusting the disc, the periphery of which carries the date,

Fig. 8 a portion of the same view showing the parts in another mutual position,

Fig. 9 a detail view of the mechanism serving, at the change of month, to adjust the disc the periphery of which carries the name of the month,

Fig. 10 a detail view of the mechanism preparing the adjustment of the date disc at the change

of month, when the date disc, all depending on the number of days of the month, has to be advanced one to four steps forward, corresponding to the month having from 31 to 28 days, and the mechanism for regulation of the adjustment in leap years.

Fig. 11 a section along the line XI—XI in Fig. 10, and

Fig. 12 a detail view of the mechanism shown in Fig. 10, in the position occupied by the parts in a leap year,

Fig. 13 shows a modified construction.

As shown in Fig. 1, the apparatus is enclosed in a casing 12, the front wall 13 of which, Fig. 2, is removed. The apparatus has two side walls 14 and 15, which are held together by means of bolts 16, 17 and 18. In the side walls a shaft 19 is journaled, on which three equally large cylindrical discs are loosely mounted, viz. the disc 20, on the periphery of which the names of the days of the week are inscribed, the disc 21 the periphery of which carries the date numbers and the disc 22, the periphery of which carries the names of the months. In the front wall 13 of the enclosing casing, Fig. 2, a rectangular opening 23 is provided, and inside of the latter there is attached to the side walls 14 and 15 an opaque shield 24 with three windows 25, which are shown with dotted lines in Fig. 1, the shield 24 itself being omitted in this figure. As shown in Fig. 1, the indication: THURS. 22 SEPT. corresponding to the momentary position of the discs 20 to 22 can be read through these window openings.

In the side walls 14 and 15, as shown in Fig. 2, a rotary shaft 26 is journaled, which on the outside of the side wall 14 supports, loosely mounted on the shaft, a double arm 27, 28, one branch 28 of which is ending in a hook 29. In the rear wall 30 of the enclosing casing, Fig. 2, a vertical coin-insertion slot 31 is provided, and inside of the latter, in a slit 32 in the side wall 14, a pin 33 is fixed, which all depending on the size of the coins can be adjusted up or down. The side wall 14 supports further a coin chute 34 open at the top and at the bottom. The end of the arm 27 projects over the coin chute 34, and when a coin 35 is introduced by way of the coin slot 31, it will pass over the pin 33, and will thereby force the arm 27 upward. When the coin has passed between the pin 33 and the arm 27, it will drop down through the coin chute 34 to a collecting receptacle disposed below the apparatus, but not shown on the drawings.

To the wall 14 a pin 36 is attached, about

which an arm 37 can rotate. This arm is fitted with a hook 38 and an extension, which projects into the coin chute 34, where it is actuated by the coin dropping through the coin chute. The arm 37 is actuated by a spring 40.

5 This part of the apparatus acts in the following manner.

When the coin 35 is pressed through the coin slot 31, it will lift the arm 27, whereby the hook 29 comes into engagement with the hook 38, so that the arm 27, 28 remains locked in this position. By the subsequent drop through the coin chute 34 the coin actuates the arm 37 in such a manner that the hook 38 releases the hook 29, and a spring 10 mentioned in the following will then return the arm 28 into the position shown in Fig. 2. The motion of the arm 27, 28 caused hereby effects the adjustment of the calendar discs 20, 21, 22, as described in the following.

20 As mentioned above, the arm 27, 28 is loosely mounted on the shaft 26. By means of a pin 41, a pawl 42 is pivoted to the arm 28, which pawl is in engagement with an eight-toothed ratchet wheel 43 on a shaft 44. On a pin 45 a check pawl 25 46 is pivoted, which similarly is in engagement with the ratchet wheel 43. A spring 47 connects the pawl 42 with the check pawl 46, and holds the two normally in engagement with the ratchet wheel 43.

30 When as shown in Fig. 2 a coin 35 is inserted, the latter will turn the arm 27, 28 in such a manner that the pawl 42 will move the ratchet wheel 43 one tooth forward in a counter clockwise direction, after which the check pawl 46 35 jumps into the next tooth space in the ratchet wheel and at the same time, as mentioned above, the hook 29 comes into engagement with the hook 38, and becomes locked by the latter as shown in Fig. 3. When now the coin drops through the 40 coin chute, it will actuate the arm 37 in such a manner that the ratchet wheel 43 is thereby rotated one tooth, i. e. one eighth of a revolution forward. This happens regularly whenever a coin is inserted.

45 To the shaft 26 there is attached, Fig. 4, behind the side wall 14 of the apparatus, an arm 48 with a bent wing 49, which projects through an opening 50 in the wall 14, and is taken along by the arm 28, when the latter is rotating, when a coin 50 as mentioned above is inserted into the apparatus. The arm 48 is further fitted with a tooth 51, which co-operates with a wheel 52 with four teeth 53. This wheel, which is shown in perspective view in Fig. 5, is mounted on the shaft 44, but behind the wall 14 and in the same plane as the arm 48, which is actuated by a spring 54.

55 The position of the wheel 52 shown by full lines in Fig. 4 corresponds to the position of the other parts in Fig. 2. By the insertion of a coin the arm 28 moves, by means of a pressure against the wing 49, the arm 48 towards the position 48' shown by dot-and-dashed lines in Fig. 4, and at the same time the wheel 52 is rotated in such a manner that a tooth 53 will come opposite the end of the tooth 51 in the position 51' of the same in such a manner that the arm 48 will be locked in the position 48', while the other members return into their normal positions, Fig. 2. When now another coin is inserted, the arm 27, 28 60 is again moved as described, but this time it does not take the arm 48 along. On the other hand it turns the wheel 52 one eighth of a revolution forward, so that no tooth 53 will now stop the tooth 51', for which reason the arm 48 now, while 65 actuated by the spring 54, can follow the return 70 75

motion of the arm 27, 28 into the position shown in Fig. 2.

The arm 27, 28 has consequently to be moved twice up and down, in order that the shaft 26 with the arm 48 may be moved once back and forth, 5 and this means that the insertion of two coins will be required for adjusting the calendar.

By means of a hook 55, Fig. 2, adapted to turn about the shaft 26, the pawl 42 can now be locked in the position 42' shown with dot-and-dashed 10 lines, so that it cannot any longer actuate the ratchet wheel 43, and the calendar members can then be adjusted merely by the insertion of one single coin, the ratchet wheel 43 and the wheel 52 being thereby set entirely out of function, and the arm 48 being now able to follow the motions of the arm 27, 28.

In order to make sure that also small coins, by dropping through the coin chute 34, will actuate the arm 37, one side wall 56 of the coin chute 20 is pivoted about a pin 57, in such a manner that it can be adjusted to fit the size of the coin.

A ratchet wheel 58, Figs. 1 and 6, with twenty-eight teeth is connected with the day disc 20. On the shaft 26 an arm 59 is attached, which at the 25 bottom is connected to a pawl 61 by means of a hinge pin 60. The said pawl is fitted with an aperture 62 encircling a shaft 63 journaled in the side walls of the apparatus, and is maintained lifted into contact with the shaft 63 by means of 30 a spring 64. The pawl 61 is fitted with a driving tooth 65 and a stopping tooth 66. When the shaft 26 by the insertion of a coin, as described above, has been turned in the direction of the arrow 67 shown in Fig. 6, the driving tooth 65 35 will come into engagement with the ratchet wheel 58 and rotate the same and the disc 20 one tooth forward, and by placing itself under the following tooth of the ratchet wheel 58 the stopping tooth 66 will prevent the said wheel from being 40 flung more than one tooth forward.

In this manner the day disc 20 is adjusted one step forward, whenever the shaft 26 is turned in the direction of the arrow 67, Fig. 6.

45 As shown in Figs. 1 and 7, a ratchet wheel 68 with thirty-one teeth is provided in connection with the date wheel 21. On the hinge pin 60 of the arm 59 there is suspended still another pawl 69 with an opening 70 enclosing the shaft 63, and also this pawl is maintained lifted up against the 50 shaft 63 by means of a spring 71. The pawl 69 supports a driving tooth 72 and a stopping tooth 73, which when the shaft 26 is turned in the clock-wise direction moves the ratchet wheel 68 one tooth forward, in the same manner as the 55 pawl 61, with the teeth 65 and 66, rotated the ratchet wheel 58 one tooth forward. In this manner the adjustment of the date disc 21 is effected normally from day to day, but at the change of month, when the month passed has less 60 than thirty-one days, and the date wheel consequently has to be moved more than one step forward, another mechanism enters into operation.

65 In firm connection with the month disc 22, Figs. 1 and 10 to 12, a disc 74 is provided, the 65 periphery of which is divided into 12 parts, and is fitted with incisions the depth of which corresponds to the number of days of the various months, in such a manner that no incisions are provided for the months with thirty-one days, 70 while on the parts corresponding to months with thirty days there are incisions 75, and on the part corresponding to the month of February there is an especially deep incision 76. To the shaft 26 a hook-shaped arm 77 is attached, which owing to 75

the action of the spring 54, Fig. 4, rests against the periphery of the disc 14. The normal position of repose for the shaft 26 and the arm 59 is thus different for the different months, and depends on the number of days of the latter. The position of the arm 59 in Figs. 6 and 7 corresponds to the hook-shaped arm 71, as shown in Fig. 10, resting against a portion of the disc 14 that corresponds to a month with thirty-one days, and the rotation of the shaft 26 in consequence of the insertion of a coin is in this case just large enough, as described above, to turn the ratchet wheels 58 and 68 one tooth forward by means of the pawls 61 and 69. In the months during which the hook-shaped arm 71 rests against the bottom of one of the incisions 15, the rotation of the shaft 26 by the insertion of a coin is somewhat greater, and in the month of February, during which the arm 71 rests against the bottom of the incision 76, still somewhat greater. Fig. 8 shows the position normally occupied by the arm 59 with the pawl 69 during the month of February, when the latter has twenty-eight days. The pawl 69 is here moved so far to the right that the shaft 63 will here be situated at one end of the incision 70.

As shown in Figs. 7 and 8, the side of the ratchet wheel 68 is fitted with a pin 78, which co-operates with an auxiliary pawl 80 suspended from a pin 79 on the pawl 69. This auxiliary pawl has one single, obliquely cut tooth 81, and is actuated by a spring 82, which lifts it up against a pin 83 fixed on the pawl 69. When the pin 78, by the rotation of the ratchet wheel 68, moves past the tooth 81, it will press the auxiliary pawl 80 downward, but when the pin has passed the tooth 81, the spring 82 will again lift the auxiliary pawl 80 up into contact with the pin 83.

The mechanism is now adjusted in such a manner that the pin 78 will pass the tooth 81 just on the last day of the month, and the next time when a coin is inserted into the apparatus, and the shaft 26 in consequence thereof is rotated, the tooth 81 will move the ratchet wheel 68 so many teeth forward, by means of the tooth 78, that the date disc 21 connected to the ratchet wheel will show the date 1.

In leap years, in which February does not have twenty-eight but twenty-nine days, the hook-shaped arm 71 must not rest against the bottom of the incision 76, but has to be maintained lifted some distance above the same. This is attained, as shown in Figs. 10 to 12, by suspending on a pin 84, on the wall 15, a lever 85 with a hook 86. The arm 85 rests normally against a stop 87 attached to the wall 15, and is in this position inoperative. In the wall 15 a rotary pin 88 is journaled, which supports a four-toothed star wheel 89 with a pin 90, which when the star wheel occupies the position shown in Fig. 12 lifts the arm 85 so far that the hook-shaped arm 71 will rest against the hook 86, and by the latter will be prevented from reaching the bottom of the incision 76 in the disc 14. On the latter a pin 91 is attached, which for each revolution of the disc, i. e. every year, adjusts the star wheel 89 one tooth forward. A spring 92, which rests along the star wheel, holds the same in position during the intervals between the rotations of the said wheel one quarter of a turn forward by means of the pin 91.

Outside of the wall 15 a disc 93 is attached on the pin 88, by means of which disc the star wheel 89 can be adjusted in such a manner that the pin 90, when the year is a leap year, will occupy the position shown in Fig. 12, where it lifts the arm

85, and when the star wheel once has been adjusted correctly, the pin 91 will adjust the same automatically from year to year. Only the skipping of the leap year every hundred years cannot be effected automatically by the apparatus in the 5 construction described.

Whenever the date wheel 21 has been given one revolution, the month disc 22 has to be adjusted one twelfth of a revolution forward. This is effected by the mechanism shown in Fig. 9. To 10 the side of the date wheel 21, a spiral-shaped disc 94 is attached, which is fitted with one tooth 95 co-operating with a nose 96 on an arm 97, which is attached to the shaft 63. About a pin 98 on the arm 97 a pawl 99 is pivoted, which rests 15 against the periphery of a gear wheel 100 with twelve teeth, which is rigidly connected to the month disc 22. A tension spring 101 connects the pawl 99 to the bolt 16. On the side of the arm 97 a stop 102 is provided. When the tooth 20 95 moves past the nose 96, and the arm 97 while actuated by the spring 101 is moved in the direction of the arrow 103, the same spring will cause the pawl 99 to engage the gear wheel 100, whereby the latter and, thereby, the month disc 22 will be 25 turned one twelfth of a revolution forward. At the same time the rotation of the arm 97 will move the stop 102 into a tooth space in the gear wheel 100, and stop the same, so that it cannot be flung too far forward.

As shown in Figs. 1 and 9, a plate spring 104 is attached to the bolt 16, which spring maintains the gear wheel 100 in its position of repose, and further as shown in Figs. 1, 6 and 7 a plate spring 105, the bifurcated body of which serves to hold 30 35 the ratchet wheels 58 and 68 in position.

The invention may be used in other constructions than the one shown on the drawings, and the details described may be replaced by other ones having the same or a similar effect. The 40 mechanism may further be supplemented by a member which shows the year, and is readjusted automatically from year to year.

A modified construction illustrated in Fig. 13 shows that the arm 27, 28 may be fixed on the 45 shaft 26, in which case the parts 41 to 54 may be omitted, and the apparatus acts then every time a coin is inserted into the mechanism. In that case the arm 27, 28 receives, by the insertion of 50 a coin, a motion the magnitude of which varies 55 with the number of days in the month concerned, in such a manner that the motion will be greatest in the shortest months.

We claim:

1. In a savings calendar, means forming a coin insertion aperture, a movable member situated within said aperture and adapted to be pushed sideways by an inserted coin, a plurality of calendar members, a movable shaft connected with 55 said calendar members and actuated by the first-mentioned movable member, an arm provided on 60 said shaft, and a disc having incisions corresponding to the months the number of days of which is less than thirty-one, said arm resting against the 65 periphery of said disc, the normal position of said shaft varying according to the number of days in the month, whereby the motion given to said shaft by the first-mentioned movable member will be of different length in the various months depending 70 on the number of days in the same.

2. A savings calendar in accordance with claim 1, wherein the first-mentioned movable member is rigidly connected with said movable shaft, the normal position of said shaft being determined 75 by the feature that said arm provided on said

shaft rests upon the periphery of said disc having incisions corresponding to the months the number of days of which is less than thirty-one, the normal position of the arm varying similarly with the number of days in the month.

5. In a savings calendar, means forming a coin insertion aperture, a movable member adapted to be pushed sideways by the inserted coin, a common shaft, a series of discs carried by said shaft and provided with calendar indications on the periphery thereof, said arm being adapted to actuate said shaft, another disc provided with incisions corresponding to the month the number of days of which is less than thirty-one, said disc being attached to said shaft, and an arm provided on said shaft and resting against the periphery of the last-mentioned disc.

6. In a savings calendar, means forming a coin insertion aperture, a movable arm situated within said coin insertion aperture and adapted to be pushed sideways by the inserted coin, a shaft, a day disc carried by said shaft, a date disc carried by said shaft, said movable arm being supported by said shaft, another arm supported by said shaft, a disc having incisions corresponding to the months the number of days of which is less than thirty-one, the second-mentioned arm resting against the periphery of the last-mentioned disc, a third arm attached to said shaft, two pawls, and a hinge pin connecting said two pawls with the third-mentioned arm, one of said pawls cooperating with said day disc when said shaft is rotated to adjust the same one step forward, the other one of said pawls simultaneously adjusting the date disc one step forward.

7. In a savings calendar, means forming a coin insertion aperture, a movable arm within said coin insertion aperture and adapted to be pushed

sideways by the inserted coin, a shaft carrying said movable arm, a day disc carried by said shaft, a date disc carried by said shaft, another arm connected with said shaft, a pawl, a hinge pin connecting said pawl with the second-mentioned arm, another auxiliary pawl connected with the first-mentioned pawl, a pin, said auxiliary pawl being pivoted about the last-mentioned pin and being fitted with an oblique tooth, a ratchet wheel connected with said date disc and provided with thirty-one teeth, a pin on said ratchet wheel, said oblique tooth being adapted to come in contact with the last-mentioned pin, the last-mentioned pin being adapted to depress said auxiliary pawl, and a spring situated behind the last-mentioned pin and adapted to raise said auxiliary pawl.

8. In a savings calendar, means forming a coin insertion aperture, a movable arm within said coin insertion aperture and adapted to be pushed sideways by the inserted coin, a shaft connected with said arm, calendar discs attached to said shaft, another arm provided on said shaft, another rotatable disc having incisions corresponding to the months the number of days of which is less than thirty-one, the last-mentioned arm resting against the periphery of the last-mentioned disc, a pin provided on the last-mentioned disc, another pin, a four toothed star wheel supporting the last-mentioned pin, the first-mentioned pin being adapted to readjust said four toothed star wheel for each revolution of the last-mentioned disc, and an arm actuated by the last-mentioned pin, the last-mentioned arm adjusting the second-mentioned arm to prevent the second-mentioned arm from reaching the bottom of one of said incisions in the month of February.

HANS JØRGEN JEPSEN.
KAI CHRISTIAN NIELSEN.
